FOREIGN PATENT DOCUMENTS

DE 202004017010 4/2005

Primary Examiner — Robin V Webster

(74) Attorney, Agent, or Firm — Ryan Kromholz & Manion, S.C.

(57) **CLAIM**

The ornamental design for a bucket insert, as shown and described.

DESCRIPTION

FIG. 1 is a perspective view;

FIG. 2 is a perspective view showing the application of the invention to a bucket;

FIG. 3 is a front elevation view;

FIG. 4 is a rear elevation view;

FIG. 5 is a right side elevation view;

FIG. 6 is a left side elevation view;

FIG. 7 is a top plan view; and,

FIG. 8 is a bottom plan view.

The broken line showing of openings in FIGS. 1, 2 and 6 form no part of the claimed design.

The bucket insert is shown with symbolic break lines in FIGS. 1, 2, 3, 4, 5 and 6; any portion between the break lines forms no part of the claimed design.

The broken line showing of a bucket in FIG. 2 forms no part of the claimed design.

1 Claim, 2 Drawing Sheets(56)
